UNITED STATES PATENT OFFICE.

LUDWIG LIPTAI, OF NEW YORK, N. Y.

BOTTLE.

No. 888,829.

Specification of Letters Patent.

Patented May 26, 1908.

Application filed February 20, 1907. Serial No. 358,402.

To all whom it may concern:

Be it known that I, LUDWIG LIPTAI, a subject of the King of Hungary, and resident of the city of New York, in the county of New York and State of New York, have invented certain new and useful Improvements in Bottles, of which the following is a specification.

The present invention relates to liquid containers, and more particularly to siphon-10 bottles.

It has for its object to provide a bottle adapted to contain an aerated or carbonated liquid, dischargeable by the pressure of the gas contained therein, and being transformable into a bottle suited to be used for any ordinary liquid, which is poured or decanted from the bottle in the usual manner.

The present invention consists of a bottle having a tube within the same, which may be integral with the walls of the bottle, and extends down into the bottle from the neck near to the bottom of the same. A faucet, comprising two independent valves, is secured to the bottle, and one discharge passage of this faucet coincides with the tube, while another registers with a comparatively larger outlet of the bottle. The two valves being independent, the contents of the bottle may be discharged through any of the outlets, as the nature of the liquid may require.

The invention is illustrated in the accompanying drawings, in which

Figure 1 is a side elevation, partly in section, of a bottle constructed according to the present invention and Fig. 2 a horizontal cross section on line 2—2 of Fig. 1.

1, in Fig. 1, designates a hollow body or bottle, made of non-metallic or vitreous material, such as glass, having a neck 2, provided with screw-threads 2'. A delivery-tube 3, integral with and extending along the wall of the bottle from the neck to near the bottom thereof, is provided, dividing the neck of the bottle into two independent 45 passages or outlets 4 and 5. It will be observed that the outlet 5 is comparatively larger in proportion to the outlet 4 of the tube 3, the purpose of which will be herein-after more fully described.

50 An apertured washer 6 of resilient material is placed upon the outlet of the neck 2, having two apertures 7 and 8, corresponding to the outlet openings 4 and 5. The aperture

7 coincides with the outlet opening 4, while the aperture 8 registers with the larger outlet 5 of the bottle.

A siphon-head or faucet 9, having inner screw-threads corresponding to the threads 2' of the neck 2, is secured by means of these threads to the neck of the bottle, and holds 60 the washer 6 firmly in place, causing a perfect contact between the neck and the siphon-head, and, therefore, a gas- and water-tight closure of the bottle. The siphon-head comprises two independent passages, *i. e.* the 65 spout 10 and the outlet 11, the former registering with the aperture 7 and the latter with the aperture 8.

12 and 13 designate two independent operating plugs, allowing of closing or opening 70 communication between the tube 3 and the spout 10 and the larger outlet of the neck and its corresponding outlet passage 11. The plug 13 is rotatably secured to the siphon-head by means of a screw 13', and carries a 75 cover 14, suited to open or close the mouth of the outlet 11 when the plug is rotated to open and close this outlet.

Each of the plugs 12 and 13 comprises a passage, leading at right angles to the axis 80 of the plug. By means of these passages communication is opened between the tube 3 and the spout 10, and the larger outlet 5 of the bottle and its corresponding outlet 11, respectively, when the passages are in line 85 with the spout 10 and outlet 11, respectively.

It is obvious that this bottle may be used as a siphon-bottle as well as for a container for any suitable liquids. In cleaning siphon-bottles the siphon head is usually removed, 90 while in a bottle, constructed according to the present invention, this will not become necessary. The bottle may be thoroughly cleaned through the larger outlet opening 11, without removing the siphon-head, and it is 95 obvious that both plugs may be opened, so as to more readily admit the water.

When the bottle is filled with an aerated or carbonated liquid, it is discharged through the spout 10 by opening the communication 100 between the tube 4 and the spout 10 by means of the plug 12, while when filled with any other not-aerated liquid, it is discharged through the larger passage 11. In filling or emptying the bottle in case of not-aerated 105 liquids, both plugs may be opened, so as to

admit air when emptying the bottle and open a passage for the air contained in the bottle when filling the same.

As new and useful is claimed and desired 5 to be secured by Letters Patent of the United States:—

1. A liquid container, comprising, in combination, a hollow body, a tube within the same integral with and extending along the 10 walls thereof, a faucet secured to said body and having two independent passages, two independent valves in said faucet and adapted to close or open said passages.

2. A liquid container, comprising, in com-

bination, a hollow body, a tube within the 15 same and integral with and extending along the wall thereof, a faucet secured to said body and having two independent passages, two rotatable valves in said faucet and adapted to close and open said passages. 20

Signed at New York, in the county of New York, and State of New York, this sixteenth day of February, A. D. 1907.

LUDWIG LIPTAI.
